UNITED STATES PATENT OFFICE.

FRANK B. JAEGER, OF MILWAUKEE, WISCONSIN.

KEYHOLE-GUARD.

1,097,639.

Specification of Letters Patent. Patented May 26, 1914.

Application filed July 25, 1912. Serial No. 781,236.

To all whom it may concern:

Be it known that I, FRANK B. JAEGER, a citizen of the United States, residing at Milwaukee, in the county of Milwaukee and State of Wisconsin, have invented certain new and useful Improvements in Keyhole-Guards, of which the following is a specification.

My invention relates to locks and particularly to padlocks.

The primary object of my invention is the provision of a protective mechanism for padlocks or other locks so constructed as to prevent the insertion of a key into the padlock except by one who knows the secret of the lock.

A further object of the invention is the provision of a lock, the keyhole whereof is closed by a door, the door being held closed by a latching device so constructed that it may be released from its engagement with the door by the insertion of a suitable instrument, the parts, however, being so formed as to be included in the general ornamentation of the lock and thus identified only by one who understands the secret of the lock.

A further object of the invention is to so construct the lock as to provide two faces, these faces having precisely the same character and appearance, one of the cases, however, having a shiftable element disposed therein, engaging with a latch, and having a door with which the latch engages, the door concealing the key opening of the lock.

Other objects will appear in the course of the following description.

My invention is illustrated in the accompanying drawings, wherein:

Figure 1 is a face view of a pad-lock constructed in accordance with my invention, the door being closed. Fig. 2 is a like view to Fig. 1 but showing the door concealing the keyhole half open. Fig. 3 is a section on the line 4-4 of Fig. 1. Fig. 4 is a fragmentary section on the line 5-5 of Fig. 1. Fig. 5 is a fragmentary enlarged section on the line 6-6 of Fig. 2.

Corresponding and like parts are referred to in the following description and indicated in all the views of the accompanying drawings by the same reference characters.

Referring to these drawings it will be seen that the pad-lock as illustrated has an ordinary form and comprises a body 2 having oppositely disposed face-plates 3 and 4. The

body of the lock is provided with the ears 6 between which is pivoted a hasp 7 and opposite the ears 6 the lock body is provided with ears 8 which are identical in shape and arrangement with ears 6. The end of the hasp passes through an opening in the plate 11 of the body, and is adapted to be engaged by any suitable bolt, as usual in locks of this character.

The mechanism whereby the bolt 19 is operated through the medium of a key may be of any suitable character and as it forms no part of my present invention, is not shown. The face plate 4 of one side of the body of the lock is slotted as at 18 for the passage of a key whereby the bolt may be operated. A guard-plate 15 is disposed between the face-plates 3 and 4 and is formed with a key-hole slot 16. The bit 25 of the key is, of course, also formed so as to be accommodated to the slot 18 and the slot 16.

The face plate 4, as before stated, is formed with the slot 18 which has, of course, the form of the key, this slot being so formed that it will only permit the insertion of a particular form of key. The slot is surrounded by an ornamental frame designated 28, this frame in the particular instance shown having the form of a door frame, the door frame comprising oppositely disposed parallel piers 29 and the pediment 30 which is triangular in form. Disposed within the pediment is a design unit 31 illustrated as having the form of a figure eight although it may have any other suitable form. This element 31, as illustrated in Fig. 5 is pivoted at one end by means of a pin, stud or rivet 32 to the face plate 4, while the other end of the element 31 is free to move vertically. This free end of the element 31 is provided with the inwardly projecting pin 33 passing through a slot 34 in the face plate, and this pin at its inner end is connected to a latch 35 illustrated in dotted lines in Fig. 2. The latch is angular in form and one end of the latch is formed with and connected to a spring 35^a which acts to force the latch downward.

The lower angular extremity of the latch is yieldingly held by the spring 35^a projecting beyond an opening 36 formed in the face plate 4 within the area inclosed by the door frame 28. Pivotaly mounted within the area inclosed by the door frame is the door 37. This door is hinged to the plate 4 in any suitable manner and preferably by pins

37^a extending into the lintel and sill of the door frame. The door is provided on its inner side face with the outwardly projecting keeper 38 with which the detent end of 5 the latching member 35 engages, as illustrated in Fig. 3, so as to hold the door closed.

The door is urged to an open position by means of a spring 39 attached to the inside 10 face of the plate 4 and having a pin 40 which projects through an opening in the plate 4 in that corner of the space surrounded by the door frame opposite to the opening 36. Thus when the latch 35 is raised and re- 15 leased from its engagement with the keeper 34 the door will be urged open by the spring 39, as shown in Fig. 2, thus disclosing the slot 18.

The plate 3 which forms the opposite 20 side of the padlock has exactly the same design as the plate 4. In other words, it is provided with an imitation door frame 28^a of precisely the same form as the door frame 28 and this frame includes a pediment 30^a 25 of the same form as the pediment 30 on the opposite face of the padlock, and within the space bounded by this pediment there is disposed a design unit or element 31^a having the same form as the element 31. This ele- 30 ment 31^a, however, is not movable but is formed as part of the face plate 3. There is no slot in the space bounded by the face plate 3 however. When the door 37 is closed, therefore, the two faces of the padlock look precisely alike. Both of them have a door frame surrounding a plain unbroken space; both of them have a pediment above the door frame; and both of them have an ornamental design unit or element disposed 35 within the pediment. There is no apparent keyhole, nor is there any indication on the face of the lock leading one to guess on which side the key is to be inserted, nor is there any indication leading one to believe 40 that there is a door in the plate 4 which when opened would disclose the keyhole. The spring 35^a has sufficient strength to hold the element 31 against ordinary pressure so that considerable experiment may be made 45 with the lock before it is discovered that one of the elements 31 is movable. As a matter of fact, it is almost impossible to discover the secret of this lock by one who does not understand its construction.

50 In the operation of the invention, when it is desired to open the padlock, it is necessary to insert a knife blade or a blade of like character below the free end of the element 31 and force it upward against the action of the spring 35^a. This will withdraw the latch 35 whereby to cause the door to open. As soon as the door opens, the key may be inserted in the slot 18 and operated in the usual manner to withdraw the bolt 19.

55 When it is desired to lock the padlock the

member is forced downward to the position shown in Fig. 1 and the key is used to project the bolt in engagement with the hasp, the key is withdrawn and the door 37 closed. As the forward end of the keeper 38 is bevelled, the closing of the door will cause an upward movement of the latch 35 and the latch will then be projected into the notch of the keeper by the spring 36.

70 While I have illustrated a particular form 75 of padlock and have illustrated a particular ornamentation as applied to the faces of the padlock, I wish it understood that other forms of locking mechanisms might be used and that other ornamental designs may be 80 placed upon the faces of the lock without in any way interfering with the principle of my invention. Furthermore, it will be 85 obvious that the principle of my invention may be applied to other locks than pad locks.

Having thus described the invention what is claimed as new is:

1. In a lock, a body having oppositely disposed face plates, one of said face plates being provided with a keyhole slot, a hinged door normally covering the keyhole slot, an angular latch disposed within the lock on the inside face of said last named face plate and adapted to operatively engage at its 90 extremity with said door to hold it closed, a design unit disposed upon the outside face of the face plate pivoted thereto and having its other end operatively connected to said latch whereby when the free end of the design unit is shifted the latch will be shifted 95 out of engagement with the door, the opposite face plate of the lock having the same general configuration and being provided with a like design unit but fixed from 100 movement.

2. In a lock, a body having oppositely disposed face plates, one of said face plates being provided with a keyhole slot, a raised frame surrounding the keyhole slot, and in- 110 cluding oppositely disposed piers and a pediment, a door hingedly mounted upon the face plate and disposed entirely within said frame when closed and having an in- 115 wardly projecting keeper, a spring actuated latch disposed on the inside of the face plate and engaging with said keeper, an ornamental member forming a design unit disposed in the pediment pivotally mounted at one end to the face plate and at its 120 other end having a portion projecting through the face plate and engaged with said latch, the free end of said ornamental member being disposed adjacent to one portion of the raised frame of the pediment 125 whereby said raised frame will form a fulcrum for engagement by an implement designed to shift the unit, a movement of the ornamental member in one direction raising the latch from its engagement with 130

the keeper, and a face plate disposed opposite the first named face plate having the same general form but being imperforate, the face of this last named plate being formed 5 with an imitation door frame comprising oppositely disposed piers and a pediment and also being formed with an ornamental member disposed within said pediment and being a duplicate of the first named ornamental member.

3. In a lock, a body having oppositely disposed face plates, one of said face plates being provided with a keyhole slot, a raised frame surrounding the keyhole slot and including oppositely disposed piers and a pediment, a door disposed entirely within said frame when closed and having an inwardly projecting keeper adapted to extend through an opening in the face plate 15 when the door is closed, said door having pintle members extending into the sill and cross bar of the pediment, a spring on the inside of the face plate having a pin projecting therethrough and contacting with

the door to urge the door to open position, 25 a latch mounted upon the inside of the face plate, one end of said latch being formed to provide a spring urging the latch into engagement with the keeper on the door, an ornamental design unit disposed within 30 the pediment adjacent to the cross bar thereof and having a pin passing through a slot in the face plate and engaging said latch, and a face plate disposed opposite the first named face plate having the same 35 general form but being imperforate and formed with an imitation door frame comprising oppositely disposed piers, a pediment and also being formed with an ornamental member disposed within said pediment and being a duplicate of the first named ornamental member.

In testimony whereof I affix my signature in presence of two witnesses.
